UNITED STATES PATENT OFFICE.

DAVID TILTON, OF HARTFORD, CONNECTICUT.

CLUTCH-GUARD.

SPECIFICATION forming part of Letters Patent No. 295,595, dated March 25, 1884.

Application filed August 27, 1883. (No model.) Patented in England December 16, 1878.

To all whom it may concern:

Be it known that I, DAVID TILTON, of Hartford, in the county of Hartford and State of Connecticut, have invented a certain new and useful Improvement pertaining to a Clutch-Guard, of which the following is a description, reference being had to the accompanying drawings, where—

Figure 1 is a top view. Fig. 2 is a side view. Fig. 3 is a view in central longitudinal vertical section on the plane $x x$.

This improvement is one in that class of devices used in machines for communicating rotary motion, and at the same time letting the parts slip or stop when some obstruction occurs which is likely to break the machinery, the device being so adjustable that this slip or stop of the rotary motion may be made to occur with the exertion of any particular amount of force or power. Devices for this purpose have existed previous to the present improvement; and my improvement consists in such combination and arrangement and construction of the parts as effectuates the desired result in an improved manner.

The letter a denotes a rotary disk fast upon the shaft b , and driven by a belt running upon the pulley e . On the side of this disk a pawl, d , is pivoted, which pawl is provided with a tooth, d' . This tooth fits into a corresponding-shaped mortise, e' , made in the periphery of the disk e , which is loose rotarily upon the shaft d , and bears upon its side, rigid with it and appurtenant to it, a pinion, f . This pinion f is intended for meshing into a gear, which gear drives other machinery, not necessary to be shown here.

The letter h denotes an extension spiral spring, which particular kind of spring is an essential feature of this present improvement. 40 This spring holds the tooth on the pawl into the mortise in the disk e , and ordinarily by this contact of this tooth and this mortise the rotary motion which the disk a has is imparted to the disk e and the pinion, and thus 45 on to the machinery driven by the gear which meshes into the pinion f ; but if some obstruction to said machinery occurs likely to break the same, then the spring h permits the free end of the pawl to rise, lifting the tooth out of its mortise, so that the disk a will continue to rotate without rotating the disk e and the machinery driven by it. As I have already said, 50 other devices have previously been used for this purpose; but experience shows that a hinged pawl held to its work by an extension spiral spring operates where all the previous devices have failed to operate, and it is this 55 particular construction of parts which forms my improvement.

I claim as my improvement—

In a guard-clutch, the combination of the rotary disk a , the toothed pawl d , pivoted on the side thereof, the peripherally-mortised disk e , bearing the appurtenant pinion f , and 60 the extension spiral spring h , all substantially as described, and for the purpose set forth.

DAVID TILTON.

W. H. MARSH.

Correction in Letters Patent No. 295,595.

It is hereby certified that in Letters Patent No. 295,595, granted March 25, 1884, upon the application of David Tilton, of Hartford, Connecticut, for an improvement in "Clutch-Guards," an error appears in the printed specification requiring correction, as follows: In line 28, the reference letter "e" should read *c*; and that the Letters Patent should be read with this correction therein to make it conform to the record of the case in the Patent Office.

Signed, countersigned, and sealed this 15th day of April, A. D. 1884.

[SEAL.]

Countersigned:

BENJ. BUTTERWORTH,
Commissioner of Patents.

M. L. JOSLYN,
Acting Secretary of the Interior.
